(57) **CLAIM**

The ornamental design for a botanical sample display container, as shown and described.

DESCRIPTION

FIG. 1 is a top isometric view from the front of a botanical sample display container showing the design;

FIG. 2 is a top isometric view from the side thereof;

FIG. 3 is a bottom isometric view from the front thereof;

FIG. 4 is a bottom isometric view from the side thereof;

FIG. 5 is a top view thereof;

FIG. 6 is a bottom view thereof;

FIG. 7 is a front view thereof;

FIG. 8 is a rear view thereof;

FIG. 9 is a side view thereof; and,

FIG. 10 is an opposite side view thereof.

The portions of the botanical sample display container shown in broken lines form no part of the claimed design.

1 Claim, 10 Drawing Sheets
